(57) **CLAIM**

The ornamental design for “wireless access point,” as shown and described.

DESCRIPTION

FIG. 1 is a front, left perspective view of a wireless access point in accordance with our new design, particularly showing antenna straightened to a first position;

FIG. 2 is a front elevation view thereof;

FIG. 3 is a rear elevation view thereof;

FIG. 4 is top plan view thereof;

FIG. 5 is a bottom plan view thereof;

FIG. 6 is a right-side elevation view thereof;

FIG. 7 is a left-side elevation view thereof;

FIG. 8 is right, rear perspective view thereof;

FIG. 9 is a cross section view taken along the line 9-9 in FIG. 2;

FIG. 10 is a cross section view taken along the line 10-10 in FIG. 2; and,

FIG. 11 is a front, left perspective view of the wireless access point of FIG. 1, showing antenna bent to a second position.

1 Claim, 8 Drawing Sheets
